UNITED STATES PATENT OFFICE

2,610,802

VARIABLE UNIT PRESSURE MULLER

Robert L. McIlvaine, Glencoe, Ill., assignor, by
mesne assignments, to Herbert Simpson Cor-
poration, Chicago, Ill., a corporation of Illinois

Application September 14, 1948, Serial No. 49,229

1 Claim. (Cl. 241—132)

1

This invention relates to improvements in mulling machines.

More particularly it has to do with a novel type of mulling machine wherein the pressure exerted by the muller wheels on the material being worked in the crib thereof is controlled by mechanical means acting through the muller wheels.

In the mulling of materials such as sand or sand mixtures high unit pressures are desirable to efficiently mix and work the material. These pressures are usually achieved by varying the weight of the muller wheels. However, some materials, particularly light bodies such as air floated clays, do not set up enough frictional resistance to the mulling operation to cause the muller wheels to rotate. Thus, it is desirable when working such materials to use light mullers with low inertia values and attain high unit muller pressures through mechanical means acting through the muller wheels.

It is, therefore, an important object of the present invention to provide a mulling machine wherein the muller wheels have a low inertia value and wherein high unit mulling pressures are attained through use of a mechanical means other than the muller wheels themselves.

A further object of the present invention is to provide a muller in which fluid actuated power cylinders are used in conjunction with the muller wheels to control the amount of unit pressure applied against the material being processed.

Another object of this invention is the provision of means for varying the unit pressure exerted on the material being mulled while the machine is in operation.

According to the teachings of the present invention there is provided a set of muller wheels of relatively light weight pivotally mounted from the crosshead or turret of a mulling machine for rolling movement in a circular path on the bedplate of the machine. The turret is rotated by a power driven center vertical shaft. A double-acting fluid-actuated power cylinder is rigidly mounted on an upper tubular extension of the turret so that its downwardly extending piston rod bears against an arm member which extends substantially axially from the muller wheel. A fluid, such as air or oil, is brought by means of a center tube and a revolving fluid type joint to a distribution control box mounted on the upper tubular extension of the turret. The valves in the control box may be suitable operated by an electrically operated control valve located adjacent the control box and supplied with elec-

2

trical energy by means of a commutator mounted on the upper end of the tubular extension.

When fluid is applied to the top of the power cylinder, pressure is exerted directly downwardly against said axially extending arm causing the muller wheel to be pressed downwardly against the material in the crib with any unit pressure up to the pressure capacity of the fluid cylinder.

When fluid is applied to the lower end of the power cylinder a reverse pressure is applied to the axial extending arm which tends to lift the muller away from the bedplate of the machine and it may be so regulated as to move the muller wheel completely out of the material being worked.

Other and further features, advantages and objects of the present invention will be readily apparent to those skilled in the art from the following detailed description of the annexed sheets of drawings.

20 On the drawings:

Figure 1 is a top plan view of the mulling machine constructed according to the teachings of the present invention.

Figure 2 is a vertical sectional view taken substantially on line II—II in Figure 1.

As shown on the drawings:

In Figures 1 and 2, the reference numeral 10 indicates generally a mulling machine including a crib having a flat base plate 11 of circular configuration having an upstanding flange 12 extending around the periphery of the plate. A cylindrical shell 14 is secured in place on the crib inside the flange 12 by a plurality of cap screws 15. A secondary vertical wall 16 fitted snugly against the shell 14 extends substantially halfway up the shell 16 and is held in place also by the cap screws 15. This secondary plate is made of a special wear resistant material as also is a wear plate 18 disposed on the base plate 11.

40 A tubular bearing support housing 19 is secured by cap screws 20 in an opening 21 in the base plate 11 and in the wear plate 18.

Rotation of the mulling apparatus is carried out by a drive shaft 23, which is journaled in 45 roller bearings 24 at the lower end of the support housing 19 and is driven by an electric motor 25 through a gear drive 26. At its upper end, the drive shaft is keyed to a turret 27 which is supported on the housing 19. Thus, as the shaft 23 is rotated the turret 27 is also rotated. An arm 28, Figure 1, extends outwardly from a sleeve portion 29 formed integral with the turret 27 to support a scraper holder 30 at the lower end of which a scraper and plow member 31 is

50 secured by cap screws 32.

The scraper is arranged to scrape material from the side and bottom walls of the crib and direct it inwardly toward the center of the crib. As the material moves inwardly it is toppled over the inner end of the scraper blade, the height of which decreases progressively toward its inner end.

As seen in Figure 1, a sleeve portion 33 on the turret 27 has an arm 34 projecting outwardly therefrom to support, through bolts 35, a curved plow blade 36. This plow blade is arranged at its innermost end 36a to scrape material from the support member 19 and is curved to urge the material outwardly as the turret rotates in the crib. The blade of the plow is of a height at its outermost portion 36b to permit material to topple thereover as the turret rotates, providing a zone in which material is in a loose tumbled condition.

Oppositely disposed in the crib of the machine and arranged to rotate with the turret 27 is a pair of conventional muller wheels 40. The muller wheels are pivotally mounted on the turret 27 by means of support arms 41 which have sleeve portions 42 pivotally mounted on axles 43 carried by the sleeve portions 29 and 33 of the turret. The support arms 41 also include an inwardly projecting arm 44 integrally formed on the support arms 41 and abutting at their inner ends on shims 43, Figure 2, positioned on a shoulder portion 45 of the turret 27 to limit the downward pivoting of the muller wheels. An inner sleeve portion 47 of each support arm is arranged to receive a muller wheel shaft 48 about which the muller wheels 40 revolve as the turret rotates.

To remove material from the crib there is provided a discharge door 51 in the floor of the crib. The door may conveniently be made in the shape of a sector of a circle, fitting in a closed position into a mating opening 52 in the wear plate 18. The door is opened by pivoting it on a hinge 53 by means of a handle 54. When the door is opened, rotation of the plow and scraper will cause material to be pushed through the door opening.

In accordance with the teachings of this invention, a tubular post 60 is mounted over the vertical drive shaft 23 with an apertured end closure plate 61 disposed over the reduced threaded upper end of the shaft 23, and held thereon by a washer 63 and lock nut 64. A bracket 66, secured across the upper end of the post 60, as by welding, is provided with depending arms 68 on the bottom surface thereof. A fluid actuated power cylinder 70 is pivotally connected on a pin 71 through each of the arms 68 having a piston rod 73 extending directly downwardly for pivotal connection with the arm 44 of the muller therebelow.

It is to be particularly noted that the piston rods 73 exert a substantially straight vertical thrust on the arms 44 and that the arms 44 are attached directly to the rocker arms 41 substantially at the hub portions of the mullers. Thus the thrust from the power cylinders is applied through the muller wheels to the material being processed in the crib.

Power is supplied to the fluid cylinder 70 by means of a fluid tight revolving joint 76 of any standard construction, which permits a portion of the joint in the bracket 66 to revolve with the bracket while the supply line 77 thereabove remains stationary. A supply line 78 inside the tube 60 delivers the fluid, either a gas or a liquid, to a control box 80 which is also conveniently

mounted alongside the tubular extension bolt 60. Since the power cylinders 70 are double acting, supply lines 82 direct fluid to the top of each cylinder while supply lines 83 deliver fluid to the bottom of each cylinder. It will be understood, of course, that the standard valve arrangements necessary for the operation of a double-acting cylinder will be incorporated in the control box 80.

The selective delivery of fluid under pressure to the various supply lines may be controlled by an electrically operated valve member (not shown) which is energized by electrical supply lines 84 and 85 through a rotating commutator (not shown).

The control box, the electrically operated valve and the commutator may be of any standard commercial design.

From the foregoing description it will be recognized that there is provided in this invention a simple, efficient means for varying the unit mulling pressure exerted on material being processed in the crib without using heavy muller wheels which have high inertia values.

In operation, when pressure is applied to the top of the power cylinder 70 it will be transmitted to the material in any predetermined quantity up to the limit of capacity of the cylinders.

When pressure is applied to the bottom of the cylinders the piston rods 73, through their pivotal connection to the limit arms 44, will pivot the muller wheels away from the wear plate of the crib thus substantially lessening the pressure exerted thereon.

It is contemplated that the device of the present invention will be used for processing materials which at some stage during the process reach a consistency where either heavy unit pressures are not desirable or the heavy mullers with high values will not turn. It is possible, with the arrangement described above, to raise the mullers during the initial stage, so that a simple mixing action by the plows is obtained. At the proper time the mullers could be allowed to bear on the material with increasing pressure until the maximum desired unit pressure is reached. This arrangement would be particularly desirable for materials such as foundry oil bonded cork sand, wall paper coatings, air floated clay, and the like.

It will, of course, be understood that various details of construction may be varied through a wide range without departing from the principles of this invention, and it is, therefore, not the purpose to limit the patent granted hereon otherwise than necessitated by the scope of the appended claim.

I claim as my invention:

A muller comprising a crib, a housing extending upwardly through the center of said crib, a turret rotatably mounted on the top of said housing and projecting upwardly therefrom, power means beneath said crib for rotatably driving said turret, parallel horizontal sleeve members spaced outwardly from opposite sides of said turret and forming a part thereof for rotation therewith, oppositely projecting axles carried by said sleeve members, a wheel support arm pivotally mounted on each of said axles and extending inwardly therefrom along said turret, a muller wheel axle mounted on the free end of each of said wheel supporting arms and extending outwardly therefrom, muller wheels rotatably mounted on each of said last mentioned axles

for rotation about parallel spaced axes adjacent but on opposite sides of a diametral line intersecting the center of said turret and moved about said crib by rotation of said turret, a bracket on said turret above said arms and extending in 5 opposite directions, a separate double acting fluid pressure cylinder pivotally connected to said bracket adjacent each end thereof and depending therefrom, actuating rods depending from said cylinders for extension or retraction with 10 respect thereto upon the admission of fluid under pressure to one end or the other of said cylinder, said wheel supporting arms having connecting arms projecting inwardly therefrom toward said turret, and pivotal connections between said actuating rods and said inwardly projecting connecting arms.

ROBERT L. McILVAINE.
